Primary Examiner — David Muller*Assistant Examiner* — Nathan Johnston*(74) Attorney, Agent, or Firm* — Muetting, Raasch & Gebhardt, P.A.(57) **CLAIM**

The ornamental design for a filter cartridge yoke, as shown and described.

DESCRIPTION

FIG. 1 is a perspective view of a filter cartridge yoke;
FIG. 2 is a left side elevation view thereof;
FIG. 3 is a right side elevation view thereof;
FIG. 4 is a front end elevation view thereof;
FIG. 5 is a rear end elevation view thereof;
FIG. 6 is a top plan view thereof; and,
FIG. 7 is a bottom plan view thereof.

The broken lines are shown for environmental purposes only and form no part of the claimed design.

The dot dash lines are included for the purpose of illustrating a portion of the article that does not form a part of the claimed design.

The filter cartridge yoke is depicted with a symbolic break in its length. The appearance of any portion of the article between the break lines forms no part of the claimed design.
